Inventor:

UNITED STATES PATENT OFFICE.

THOMAS C. BUNTING, OF PHILADELPHIA, PENNSYLVANIA.

BOTTLE-STOPPER COVER.

SPECIFICATION forming part of Letters Patent No. 372,892, dated November 8, 1887.

Application filed March 21, 1887. Serial No. 231,802. (Model.)

To all whom it may concern:

Be it known that I, THOMAS C. BUNTING, a citizen of the United States, residing at Philadelphia, in the county of Philadelphia and State of Pennsylvania, have invented certain Improvements in Bottle - Stopper Covers, of which the following is such a full, exact, and clear specification as to enable any one to make and use the same.

10 The object of my invention is to provide a device for protecting the lips and necks of bottles for medicines and chemicals from an accumulation of dust, and also to protect and shield the stopper from extraneous contact 15 when out of the bottle. I attain this object by means of the cover illustrated in the accompanying drawings, in which—

Figure 1 shows a section of the cover as attached to a stopper of the form ordinarily used 20 for chemicals. Fig. 2 shows an elevation of a cover detached from a stopper, and Figs. 3 and 4 show the cover applied to various forms of stoppers.

Similar letters refer to similar parts in all 25 the figures.

The stopper-cover is made in the form of a frustum of a cone of any suitable material, the seam overlapping at A A, and being held loosely in contact by the single rivet B. The 30 upper part of the conical frustum has formed in it a groove, C C, this groove curving inward. The upper edge of the cover is also curved inward, as shown at D D, forming a flange, and between the flange D D and the groove C C there is thus formed a channel, E, which receives the head of the stopper F. The 35 elasticity of the metallic cover causes the channel E to hold the stopper F with sufficient firmness to keep the cover from falling off or becoming separated from the stopper in ordinary use; but if it is desired to remove the cover from the stopper a slight pressure on the cover below the rivet B will cause the upper part of the conical cover to open slightly 40 and permit it to be removed with ease from the stopper.

The cover is always made longer than the stopper itself, so that when the stopper and cover are set down upon a table or elsewhere the lower part of the cover will prevent the 50 end of the stopper from coming into contact with the table, and thus prevent any dust or foreign matter from being introduced into the bottle when the stopper is replaced. In this way a very frequent source of contamination 55 to delicate materials will be prevented. When the stopper is in the bottle, the cover protects the lip of the bottle from dust and avoids the coating of dust and medicine which otherwise often occurs.

It is evident that the cover must not be soldered or otherwise rigidly fastened together, as it would then be very difficult to attach or remove.

I am aware that covers have been used in 65 connection with bottle-stoppers, being either made in one piece with the stopper or otherwise rigidly attached, and I do not desire to claim such a cover, broadly.

What I do claim as my invention, and desire to secure by Letters Patent, is—

1. The combination of a stopper and open tube, the said tube being closed at one end by the head of the stopper, around which said tube is removably attached and from which it 75 extends downward outside of and covering the neck of the bottle, the lower edge of said tube projecting below the lower end of stopper, substantially as described, and for the purpose set forth.

2. A stopper-cover composed of a conical tube of sheet metal grooved at the top to receive the head of the stopper and held together by a single rivet, so as to be readily detachable from the stopper by the application of a 85 moderate pressure.

THOMAS C. BUNTING.
